UNITED STATES PATENT OFFICE.

ALEX DOW, OF DETROIT, MICHIGAN, ASSIGNOR TO WORTHINGTON PUMP AND MACHINERY CORPORATION, OF NEW YORK, N. Y., A CORPORATION OF VIRGINIA.

CONDENSER CIRCULATING SYSTEM.

Application filed November 6, 1920. Serial No. 422,139.

To all whom it may concern:

Be it known that I, ALEX Dow, a citizen of the United States, residing at Detroit, county of Wayne, and State of Michigan, have invented certain new and useful Improvements in Condenser Circulating Systems, fully described and represented in the following specification and the accompanying drawings, forming a part of the same.

10 This invention relates to improvements in circulating water systems for multiple circulation surface condensers.

It is the especial object of the invention to provide an improvement in the circulating water systems of multiple circulation surface condensers constructed and arranged to obtain a balanced column effect upon the circulating water passing through the condenser, in which a circulating pump or 20 pumps and two or more ascending columns of water and a similar number of descending columns are employed, the weight of the descending columns acting to reduce the work of the pump or pumps.

25 In condenser circulating systems of this class, considerable difficulty has been experienced due to breaking of the descending columns of circulating water, caused by different siphon effect resulting from unequal pump action and therefore unequal quantities of water passing through the different circulating systems, or from air leaking into one of the water lines to such an extent as to interfere with the siphon effect on one or the other of the drop legs, so that the pump supplying such drop leg works against a greater head than the other pump. Such leakage air collects in the elbows or tops of the drop legs, so that the level of the water 30 in that leg is lower than in the other, and thus the head on that leg is reduced and the head on the pump correspondingly increased. As the pump head is thus increased, less water will be forced through such drop leg 40 by the pump, thus interfering with the efficient and uniform action of the condenser system. The present invention overcomes this difficulty, in that the water in the drop leg receiving the most water acts to withdraw 45 the air from the elbow of the other drop leg and restore the proper action, so that both pumps will operate under the same head and with the same siphon effect. In case 50 only one circulating pump is used, the flow in one drop leg will aid the flow in the other

drop leg when, due to any of the above causes, such flow is below normal.

For a full understanding of the invention, a detailed description of a construction embodying one preferred form thereof, 60 will now be given in connection with the accompanying drawing forming a part of this specification, and the features forming the invention then specifically pointed out in the claims.

65 Figure 1 is an end elevation and partial section of a condenser with dual circulating water systems, and

Figure 2 is a vertical section through the water box of the condenser head.

70 Referring now to the drawing, 1 represents the condenser, 2, 2' circulating water inlet pipes leading from a pump or pumps (not shown), and 3, 3' are the usual barometric drop legs leading to the ordinary hot well. As shown in Fig. 2, the condenser is divided into four longitudinal compartments by the partitions 6, 7, so that the cooling water entering the water head through inlet 2 traverses the full length of the compartment with which such inlet is connected and returns through the compartment directly above, passing out through outlet 3. The same circulation occurs on the other side 75 of the condenser, the water entering through inlet 2' and passing out through outlet 3'. There is thus provided, in the present showing, a condenser having two double pass circulating systems.

80 In multiple circulation surface condensers working on the balanced column principle, the difficulties above stated, due to the presence of air pockets and unequal siphon effect in the legs 3, 3', is entirely overcome by the provision of cross-over connections 4, 4' 85 extending from the elbow or top of each drop leg over and down into the opposite drop leg. It will be seen that the leg 3' is tapped at its elbow or uppermost point by the pipe 4, which latter is crossed over and 90 tapped into the elbow of leg 3, the outlet 5 of such cross-over connection being situated at a point sufficiently low with respect to its inlet to obtain the full benefit of the ejecting action of the descending column in drawing off any air tending to accumulate in the elbow or upper portion of leg 3'. The cross-over connection from the top of leg 3 to leg 3' is exactly the same as the connection from 95 leg 3' to leg 3, just described.

100 105 110

It will be obvious that my invention is applicable to the circulating water systems of condensers of various types, and may be applied in connection with the circulating systems of a plurality of single circulation condensers, and to any other liquid circulating systems where the results aimed at are necessary or desirable.

What I claim is:

- 10 1. The combination with liquid circulating systems having independent drop leg outlets, of cross-over connections between each outlet and the other drop leg below the level of the liquid therein.
- 15 2. The combination with the independent outlets of condenser circulating systems, of pressure equalizing and air removing connec-

tions from each outlet above the liquid level to another outlet below the liquid level.

3. The combination with a condenser having multiple circulation with independent outlets, of pressure equalizing and air removing connections from each drop leg above the liquid level to another drop leg below the level of the liquid.

4. The combination with condenser circulating drop legs 3, 3', of cross-over connections 4, 4' from one drop leg above the liquid to the other drop leg below the liquid, substantially as and for the purpose specified.

In testimony whereof, I have hereunto set my hand.

ALEX DOW.
